CLAIM

The ornamental design for a pen holder, as shown and described.

DESCRIPTION

FIG. 1 is a top, front, left side perspective view of a pen holder, showing our new design;

FIG. 2 is a top, front, right side perspective view thereof;

FIG. 3 is a top, rear, right side perspective view thereof;

FIG. 4 is a top, rear, left side perspective view thereof;

FIG. 5 is a bottom, front, left side perspective view thereof;

FIG. 6 is a bottom, front, right side perspective view thereof;

FIG. 7 is a bottom, rear, right side perspective view thereof;

FIG. 8 is a bottom, rear, left side perspective view thereof;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The dot-dash broken lines in the figures and the lightened areas within the dot-dash broken lines show environmental subject matter that form no part of the claimed design.

1 Claim, 14 Drawing Sheets
